UNITED STATES PATENT OFFICE

CAESAR L. WILSON, OF DASSEL, MINNESOTA

HOLDER FOR COWS' TAILS

Application filed May 7, 1931. Serial No. 535,579.

It is the object of this invention to provide a novel and improved holder for cows' tails which will effectively prevent the cow from switching its tail while the cow is being 5 milked.

To this end, the invention consists in the novel parts and novel combinations of parts hereinafter defined in the claims and described in the following specification, made 10 in connection with the accompanying drawing, wherein like reference characters refer to the same or similar parts throughout the various views and in which,

Fig. 1 is a view in side elevation illustrating the holder applied to a cow's tail; and

Fig. 2 is a plan view of the holder, the parts being shown in full lines with the jaws being closed against each other and one of the jaw members being shown in 20 dotted lines in the position it will assume when the two jaws are spread apart.

In accordance with the present invention, there is provided a pivot stud 3 illustrated in the drawing as being a nutted bolt. Applied to this pivot stud are a pair of jaw members 4 and 5 respectively, which are shown as being constructed from wire. The jaw member 4 has its two ends looped about the pivot stud 3 at one side of the center 25 thereof and then projects both forwardly and rearwardly from the pivot stud. The forward and rearward portions running from the ends of member 4 are reversely bent and join in a loop formed about the pivot 30 stud 3 at the opposite side of the center of the stud from the looped ends of the member. The portion of the member 4 forwardly from the pivot stud 3 forms a curved jaw 4a of general U-shape, the forward end of 35 the jaw connecting the two arms of the jaw being considerably laterally offset from the said arms. The portion of the member 4 extending rearwardly from the pivot stud 3 is bent at substantially right angles to the 40 jaw 4a to form a handle portion 4b. The other jaw member 5 has its two ends also looped about the pivot stud 3 at one side of the center thereof inwardly from the connecting loop of the jaw member 4 and the 45 member 5 projects both forwardly and rear- 50

wardly from the looped ends. The forward and rearward portions of member 5 extending from the ends of the member are reversely bent and join in a loop formed about the pivot stud 3 at the opposite side of the center of the stud from the looped ends of the member and centrally disposed from the looped ends of the jaw member 4. The portion of the member 5 forwardly from the pivot stud 3, forms a curved jaw 5a of general U-shape, the forward portion of which is bent quite sharply laterally relative to the arms of the jaw and toward the laterally bent forward portion of the jaw 4a. The jaw 5a is slightly longer than the jaw 4a as shown and the arms of the jaw 5 are more closely spaced than the arms of the jaw 4a. The upper arm of the jaw 5a has an upwardly projecting reverse bend forming what may be called a spike 5b. The upper arm of the jaw 5a is located considerably below the upper arm of the jaw 4a and the spike 5b projects upwardly to a point well above the level of the upper arm of the jaw 4a. The rearwardly extending portion of the jaw member 5 forms a handle 5c bent as shown to form a suitable grip for the hand of the user. A coiled spring 6 encircles the pivot stud 3 at the intermediate portion thereof and this spring has one hook end which is applied about the handle portion 4b and another hook end which is applied about the handle portion 5c. This spring exerts resilient pressure on the two jaw members 4 and 5 to maintain the forward portion of the jaw 4a in abutment with the forward portion of the jaw 5a.

In using the device, in connection with the milking of a cow, the handles 4b and 5c will be grasped by one hand of the milker to spread the two jaws 4a and 5a apart. The fringe of hair H of the cow's tail T will then be carried downwardly over the spike 5b so that the spike extends completely through the hair of the tail. The tail of the cow will then be looped by the milker as shown in Fig. 1, and the looped portion of the tail will be placed between the two jaws 4a and 5a as shown. The jaw members may then be released, whereupon the jaws 4a and 5a clamp 100

against the looped portion of the cow's tail. When the tail is held in this position, it will be impossible for the cow to switch its tail and the matted hair H at the end of the cow's tail fitting over the spike 5b will prevent the cow from releasing the looped portion of the tail from the holder. The matted and tangled hair at the end of the tail will engage the spike 5b to prevent relative movement between the hair and the spike. The tail will be effectively held out of the way at all times. By locating the upper arm of the jaw 5a below the upper arm of the jaw 4a, there is plenty of room for the accommodation of the fringe 15 of hair H between these two arms.

Although the present device has been constructed from wire, it will be understood that any suitable material may be substituted therefor. It is essential that a pair of pincher-like jaws be provided, one of which jaws has a spike carried thereon over which the fringe of hair at the end of the cow's tail may be placed. The device has been successfully demonstrated in actual practice.

25 It will, of course, be understood that various changes may be made in the form, details, arrangement and proportions of the various parts without departing from the scope of the present invention.

30 What is claimed is:—

1. A holder for cows' tails comprising, a pair of jaw members pivoted together, resilient means urging said jaw members toward each other and an upwardly projecting spike 35 formed on one of said jaw members whereby a cow's tail may be looped and placed between said jaw members with the fringe of the cow's tail forced over said spike.

2. A holder for cows' tails comprising, a 40 pair of jaw members pivoted together at a point intermediate their length and having concave jaws projecting forwardly from their pivot to surround the looped tail of a cow, resilient means urging the concave jaws of 45 said members together and a spike formed on one of said jaws adapted to be inserted through the fringe of the cow's tail.

3. The structure defined in claim 2, the 50 jaw having said spike formed thereon being of considerably narrower width than the jaw of the other member and the upper edge of the jaw having said spike formed thereon being disposed below the upper edge of the other jaw, said spike projecting upwardly 55 from the upper edge of the jaw having the spike formed thereon.

4. The structure defined in claim 2, portions of said jaw members oppositely disposed from said pivot relative to said jaws forming 60 handles.

In testimony whereof I affix my signature.
CAESAR L. WILSON.
